[57] CLAIM

I claim the ornamental design for cover for a utility pole, as shown and described.

DESCRIPTION

FIG. 1 is an isometric view of a cover for a utility pole showing my new design;

FIG. 2 is a top plan view thereof, the bottom plan view being a mirror image of that shown;

FIG. 3 is a front elevational view thereof;

FIG. 4 is a rear elevational view thereof; and,

FIG. 5 is a right elevational view thereof, the left side elevational view being a mirror image of that shown.
